UNITED STATES PATENT OFFICE

106,150

DESIGN FOR A COMBINED RING AND HANDKERCHIEF

David E. Schwab, New York, N. Y.

Application August 2, 1937, Serial No. 70,790

Term of patent 7 years

To all whom it may concern:

Be it known that I, David E. Schwab, a citizen of the United States of America, residing in the city of New York, county of New York, and State of New York, have invented a new, original, and ornamental Design for a Combined Ring and Handkerchief, of which the following is a specification, reference being had to the accompanying drawing, forming part thereof.

The figure on the drawing is a plan view of a combined ring and handkerchief embodying my new design.

My design is characterized by the jewelled ring suspended from one corner of the handkerchief in combination with the jewelled ornament arranged as shown.

I claim:

The ornamental design for a combined ring and handkerchief, substantially as shown and described.

DAVID E. SCHWAB.
